BOWLING BALL HANDLING AND RETURN MECHANISM

George Fried, Stamford Conn., assignor to American
Machine & Foundry Company, a corporation of New
Jersey

Filed Mar. 16, 1960, Ser. No. 15,297
15 Claims. (Cl. 273—49)

The present invention relates to bowling ball handling apparatus and more particularly to mechanism for removing a bowling ball from the pit of a bowling alley and delivering it to a ball return system for return to the head end of the alley.

The invention is characterized by the provision of an upwardly extending movable ball track and a coacting endless conveyor, such as an endless belt conveyor spaced therefrom, located in the pit of a bowling alley. The lower extremity of the ball track is mounted in spaced relationship above the upper lap of the travelling pit conveyor, a distance less than the maximum diameter of a bowling ball. A ball thrown or rolling into the alley pit and onto a suitable conveyor located therein engages or is moved against the pit cushion or backstop which retards its momentum. A ball, thus slowed, is deposited in a guide channel extending transversely of the pit. In accordance with a preferred form of the invention, this guide channel, delivers a ball generally obliquely across the pit to one side thereof and through an opening in the lower portion of the cushion beneath a nose formed on the lower extremity of the ball track and into the bight formed by the ball elevating conveyor and the substantially vertically-movable ball track. A ball moving into the space between the endless belt conveyor and the ball track displaces the track vertically momentarily. As soon as the ball is engaged the belt conveyor and held thereby on the track, the track drops by gravity and the rotation of the ball thereon to its initial position. At the upper end of the track, the ball is discharged from engagement with the ball track and belt conveyor with a positive forward rolling movement onto the return rails of the ball return track. The fact that a ball being elevated maintains the track down, prevents another ball from being elevated thereby insuring proper spacing of balls and elimination of damage to balls by one striking against another. This arrangement also prevents the obstruction of movement of one ball by another on the return runway which might result in the failure of balls to reach the storage rack at the head end of an alley.

In a modified form of the present invention, the movable ball track is replaced by a fixed ball track having a spring-loaded guide or nose at its lower extremity. The guide is spaced from the upper lap of the pit conveyor a distance less than the maximum diameter of a bowling ball. A ball directed thereto, urges the track nose upwardly as it moves into the bight formed by the ball elevating conveyor and the ball track. A ball thus engaged by the ball track and ball conveyor is travelled upwardly from the spring-loaded nose onto the fixed ball track for delivery onto the rails of a ball return track.

In order to prevent the entry of a ball directly from the playing surface of a bowling alley into the ball return mechanism, there is provided, in another modified form of the present invention, a ball guide channel having a portion thereof adjacent the ball return mechanism extending into the space between adjacent bowling alleys. The pit cushion is likewise provided with a portion thereof in the path of travel of a ball moving along the alley gutter aligned with the ball return mechanism. Thus any ball entering directly into the return mechanism engages some portion of the pit cushion and has its momentum dissipated.

It is therefore an object of this invention to provide a

2

novel bowling ball elevating and return device which is simple in construction and operation and which can be located in the pit of a bowling alley so that the time required in returning a ball to a player at the head end of the alley is greatly decreased.

It is an object of the invention to provide in a ball return mechanism a ball elevating conveyor and a track spaced therefrom less than the maximum diameter of a bowling ball and means mounting at least a portion of the track for upward vertical movement relative to the ball conveyor by a ball engaged therebetween.

It is an object of the present invention to provide, in a ball return mechanism, a ball elevating conveyor and a track spaced therefrom less than the maximum diameter of a bowling ball and means mounting the track for upward vertical movement relative to the ball conveyor by a ball engaged therebetween.

It is an object in the preferred embodiment of the invention to provide, in a ball return mechanism, a ball elevating conveyor and a track spaced therefrom less than the maximum diameter of a bowling ball which is operative to elevate one ball and is so mounted for movement relative to the conveyor that while one ball is being elevated, another ball cannot be lifted.

It is an object in a modified form of the invention to provide, in a ball return mechanism, a ball elevating conveyor and a track spaced therefrom less than the maximum diameter of a bowling ball which is mounted for upward pivoting movement relative to the ball conveyor by a ball engaged therebetween.

It is another object in a modified form of the invention to provide, in a ball return mechanism, an upwardly extending, preferably vertical ball elevating conveyor and a ball track spaced from the conveyor less than the maximum diameter of a bowling ball, the track having fixed rails and a lower ball guide resiliently connected to the fixed rails and movable theretoward by a ball engaged between the conveyor and the ball return track.

Another object of the invention is to provide a ball guide channel in the pit of a bowling alley for assisting in the movement of balls deposited in the pit into the range of operation of a ball return mechanism.

Another object of a modified form of the invention is to provide a novel ball return mechanism which is located in the pit of a bowling alley and which is so constructed that balls delivered into the pit are controlled in their movement from entering directly into the ball return mechanism.

The foregoing and other objects, features and advantages of the invention, and the manner in which the same are accomplished will become more readily apparent upon consideration of the following detailed description of the invention taken in conjunction with the accompanying drawings which illustrate preferred and exemplary embodiments of the invention; and wherein like characters of reference have been applied to corresponding parts throughout the several views which make up the drawings.

FIGURE 1 is a partial side elevation of the pit of a bowling alley provide with the preferred embodiment of the invention.

FIGURE 1A is a cross-sectional view of the pit conveyor support and ball guide members taken along approximately the longitudinal centerline thereof.

FIGURE 2 is a front view of the preferred embodiment of the invention.

FIGURE 3 is a plan view of the pit of a bowling alley with the preferred embodiment of the invention showing the preferred form of the ball guide channel.

FIGURE 4 is a front view partly in section, of the pit of a bowling alley illustrated in FIGURE 3.

FIGURE 5 is a partial side elevation of a modified form of the invention.

FIGURE 6 is a partial side elevation of another modified form of the invention.

FIGURE 7 is a partial plan view of the pit of a bowling alley illustrating a modified form of ball guide channel.

FIGURE 8 is a view taken on line 8-8 of FIGURE 7.

Referring to FIGURES 1 and 2, the preferred embodiment of the invention is shown mounted in the pit P of a conventional bowling alley A between kickbacks K and K1 thereof. In the illustrated embodiment, pit P is provided with a travelling pit-wide conveyor 10 which conducts pins and balls delivered thereto from the playing surface of alley A rearwardly of pit P in the direction of arrow C, FIGURE 1. Conveyor 10 is preferably formed of a resilient material having a high coefficient of friction; such as, rubber or rubber-impregnated canvas. Conveyor 10 which preferably is in continuous motion in pit P, describes a path of travel around rollers 12 and 14 mounted on generally inclined transverse shafts 16 and 18, respectively. Shafts 16 and 18 are supported in suitable bearings at each end in kickbacks K and K1. One end of shaft 18 is provided with a sheave 20 about which belt 22 passes. Belt 22 is driven from any suitable power source (not shown) such as the main machine drive of an associated automatic bowling pin spotting machine (not shown). Belt 22 thus operates to rotate sheave 20, shaft 18 and roller 12 to drive conveyor 10 rearwardly in pit P.

To stop the forward movement, retard the momentum of bowling balls thrown into pit P and effect the separation of pins and balls in the pit, there is provided a transverse pitwide cushion or backstop 24. Cushion 24 is mounted on spaced arms 26 mounted on and downwardly depending from a shaft 28 supported by kickbacks K and K1. The bottom edge of cushion 24 is spaced from the upper lap of conveyor 10 a distance greater than the maximum diameter of a bowling pin but less than the maximum diameter of a bowling ball. Thus pins on conveyor 10 can pass freely beneath cushion 24, but balls cannot.

Mounted beneath the upper lap of conveyor 10 is a support platform or bounce board 32 secured to brackets 34 fixed to kickbacks K and K1. Bracket 34 fixed to kickback K1 is slightly higher in elevation than its corresponding bracket 34 fixed to kickback K. This arrangement provides platform 32 with a downward pitch or incline from kickback K1 towards K. Adjacent one edge of platform 32 there is provided an inclined ball guide element 36 having an oblique tapered edge 37 extending transversely across pit P, guide element 36 being mounted on platform 32 with an incline opposite to the direction of travel of conveyor 10 (see FIGURE 1A). Co-acting with guide element 36 is a second guide element 38 mounted towards the front of platform 32 beneath conveyor 10. Guide element 38 is provided with a bevelled edge 39 which complements edge 37 of guide 36 and forms an oblique ball guide channel 40 extending transversely across pit P between kickbacks K and K1.

Balls thrown on alley A usually have sufficient speed to cause an arc of trajectory greater than the space provided in pit P. A ball impacting or engaging cushion 24 urges it backwards, pivoting its supporting shaft 28 mounted in suitable bearings 30 in kickbacks K, K1. In this manner a ball engaged by cushion 24 is deflected onto the upper lap of conveyor 10 above guide element 36. Such ball gravitates on guide element 36 into ball channel 40 and whence it rolls across pit P towards kickback K. Pins on conveyor 10 are moved over ball channel 40 and guide element 36 beneath pit cushion 24 towards the rear of pit P. A ball delivered into pit P without sufficient forward momentum to engage pit cushion 24

ion 24 drops onto conveyor 10 above guide element 38 and rolls into channel 40 and thence therealong towards kickback K. Thus balls, regardless of the momentum with which they are delivered into pit P because of the fact that channel 40 is located at a relatively steep angle relative to the direction of rearward movement of conveyor 10, are speedily conducted transversely across pit P towards kickback K. Also the friction between conveyor 10 and a ball thereon causes the ball to be forced against edge 37 and maintained thereagainst while at the same time it moves transversely and obliquely along channel 40. It will be noted that the steeper the incline of channel 40, the faster a ball will traverse it.

Adjacent kickback K at the end of oblique ball channel 40, platform 32 is provided with a pair of spaced ball guides 42 mounted on platform 32 parallel to kickback K forming a second ball channel 44 parallel to the longitudinal axis of alley A. Therefore, a ball delivered into pit P is conducted obliquely and across, and then rearwardly thereof. Aligned with ball channel 44 is a suitable cutout 46 in pit cushion 24 which permits the passage of balls in channel 44 past cushion 24 to the ball return mechanism, designated generally 50.

In the preferred embodiment ball return 50 includes a ball elevating conveyor 52 which describes a generally vertical path of travel about rollers 54 and 56 mounted on upper and lower shafts 58 and 60, respectively. Shaft 60 is suitably supported at each end in spaced side plates 62 which together with front and rear plates 63 and 65, respectively, forms a housing for the ball elevating conveyor drive mechanism. Rear plate 65, in turn, is fixed to bracket 64 secured to channel 66, extending transversely of pit P and suitably attached at each end to kickbacks K and K1. Shaft 60 has a portion thereof extending through one side plate 62 and kickback K on the end of which is mounted a sprocket 68. Mounted on sprocket 68 is a drive chain 70, the other end of which passes over a sprocket 72 fixed to shaft 18 between kickback K and sheave 20. Thus, belt 22 also drives conveyor 52.

Shaft 58, which carries roller 54, is rotatably supported between a pair of spaced arms 74, secured to a sleeve 76, fastened to shaft 78 parallel to shaft 58. Shaft 78 is suitably mounted in bearings 80 fixed to crossframe 82 secured transversely of pit P to kickbacks K and K1. One end of shaft 78 extends through kickback K and mounts an arm 84. The free end of arm 84 is provided with a pin 86 which supports one end of a suitable tension spring 88. The other end of spring 88 is fixed to a stud 89 attached to the outer face of kickback K. Spring 88 functions to pull arm 84 down and maintain conveyor belt 52 properly resiliently tensioned.

Spaced from the ball engaging lap 53 of conveyor 50 is a ball track, which as shown comprises a pair of laterally spaced rails 90 fixed to vertically spaced crossframes 92. Rails 90 preferably are of hollow round cross section. Rails 90 are mounted in longitudinally spaced relationship with the ball engaging lap 53 of conveyor 56 a distance less than the maximum diameter of a bowling ball. Cross frames 92 are supported for vertical movement on vertically spaced horizontal support rods 94 fixed to bracket 96 secured to the inner face of kickback K. Thus, rails 90 are mounted for freely sliding upward movement. The lower extremities of rails 90 are provided with a transverse ball guide element 98 having a rounded nose section 99. Upper rod 94 is positioned in its associated frame 92 to limit the downward movement of rails 90 such that element 98 is spaced from the upper lap of conveyor 10 a distance less than the maximum diameter of a bowling ball. It will be understood that the ball track comprising rails 90 and guide 98 with nose section 99 and conveyor 52 are located substantially in alignment with pit cushion cutout 46 and ball guide channel 44 (see FIGURES 2 and 3).

In operation, a ball deposited on conveyor 10 upon coming under the influence of ball channel 40, as de-

scribed hereinabove, gravitates or is urged therein across pit P towards kickback K onto that portion of conveyor 10 above ball channel 44. A ball so positioned on conveyor 10 and in ball channel 44 rolls or is moved by conveyor 10 through pit cushion cutout 46 into the range of operation of bar return 50 where it engages nose 99 of ball guide 98. Since guide element 98 is spaced from the upper lap of conveyor 10 a distance less than the maximum diameter of a bowling ball, a ball moving past pit cushion 24 travels next beneath nose 99 and guide element 98. This action causes guide element and rails 90 to be moved upwardly whereupon the ball enters the bight formed by ball engaging and lifting lap 53 of conveyor 52 and rails 90.

As a ball enters the space or bight between track 90 and conveyor belt lap 53, track 90 is moved vertically. However, when on the ball begins its upward travel gravity and the clockwise rotation of a ball engaged by lap 53 of conveyor belt 52 (as viewed in FIGURE 1) causes a downward movement of track 90, the ball is then rolled while resiliently frictionally engaged on track 90 by conveyor lap 53 of 52 upwardly along track or rails 90 to an elevated point of discharge at the upper extremity of track 90. The construction and operative relationship of the mechanism described is such that when a ball is discharged over rounded guide nose 101 of horizontal ball support track 100 forming a path of return runway T, it is given a positive forward rolling movement by conveyor lap 53, thereby assisting in and expediting its return along return track T to the head end of the alley.

It should be noted that as a result of the relocation of tracks on rails 90 in their initial position (FIGURE 1) as long as a ball is positioned between track 90 and belt lap 53, nose 99 will block the entry of another ball into the bight between track 90 and conveyor 52. Thus the construction prevents more than one ball from being elevated at the same time.

As the ball is travelled upwardly by conveyor 52 along rails 90 such ball has a tendency to urge conveyor 52 downwardly away from rails 90. However, it is necessary to maintain the ball lifting lap of conveyor 52 in spaced relationship with rails 90 and to provide adequate tension on conveyor 52 during the ball lifting operation for proper ball delivery. Hence, as a ball is elevated along rails 90, arms 74, supporting shaft 58 tend to move downwardly, rotating shaft 78 in bearings 80 in a counter clockwise direction as viewed in FIGURE 1. It will be understood however, that arm 84 on shaft 78, with its associated tension spring 88 opposes such movement by arms 74, maintaining the ball lifting lap of conveyor 52 in spaced relationship with rails 90 and providing the proper tensioning of conveyor 52.

To ensure proper drive of conveyor 52 without slippage there is provided a roller 102 supported on shaft 104 fixed inside plates 62 which co-acts with drive roller 56 of conveyor 52. The return lap of conveyor 52 passes between roller 102 and roller 56 as shown in FIGURE 1, the position of roller 102 increasing the amount of conveyor 52 in contact with drive roller 56, thus ensuring adequate positive drive of conveyor 52 without slippage, ensuring proper ball return delivery.

It will be understood further, that since rails 90 are held downwardly away from conveyor 10 while in use, thereby preventing the entry of another ball, only one ball at a time can be engaged by conveyor 52 for delivery to tracks T of the ball return track, ensuring adequate spacing of balls on the ball return track preventing damage from collision therebetween.

In a modified form of the present invention, illustrated in FIGURE 5 and in which like numbers designate like parts, there is provided for coaction with conveyor 52, a pair of spaced rails 190. Each rail 190 is mounted on a pair of spaced upper and lower links 192 and 194, respectively (only one of which is shown).

Links 192 are rotatably supported on a transverse

end of each link 192 being suitably pinned to its associated shaft 196 fixed to the inner face of kickback K, the lower associated rail 190. Links 194 in turn are rotatably mounted in common on a shaft 198, fixed to the inner face of kickback K directly below shaft 196. The lower end of each link 194 is suitably pinned to its associated rail 190 directly below and in parallel relationship with upper link 192. Thus links 192 and 194 form a parallelogram, ensuring vertical movement of rails 190 relative to the ball lifting lap of conveyor 52. The lower extremities of rails 190 are provided with a ball engaging guide element 200 having a rounded nose section 201. Upper links 192 are positioned relative to pit cushion shaft 23 such that the lower portion of links 192 rest thereagainst with element 200 spaced from the upper lap of conveyor 10 less than the diameter of a bowling ball.

In operation a ball passing through pit cushion cutout 46 pivots nose 200 and its associated rails 190 upwardly as the ball moves into the bight formed by conveyor 52 and rails 190, nose 201 ensuring positive engagement of a ball by conveyor 52. Such ball is frictionally engaged therebetween and travelled by conveyor 52 upwardly along rails 190 to an elevated point of discharge at the upper extremity of rail 190. At the point of discharge rails 190 are provided with a generally horizontal support 202 having a nose section 203 which is operative with conveyor 52 to release balls from between conveyor 52 and rails 190 and conduct them onto a suitable ball return track (not shown).

In another modified form of the present invention, illustrated in FIGURE 6 and in which like numbers designate like parts, there is provided for coaction with conveyor 52 a pair of spaced rails 290 fixed in spaced relationship with conveyor 52 on spaced upper and lower brackets 292. Brackets 292, are, in turn, supported in the inner face of kickback K. Adjacent the lower extremity of rails 290 is a ball guide element 294, having a rounded nose section 295. Guide element 294 is pivotally mounted on a shaft 296 fixed to the inner face of kickback K. Element 294 is provided with a stud 298 to which is mounted one end of a suitable compression spring 300. The other end of compression spring 300 is fixed to a stud 302 provided in lower bracket 292. Lower bracket 292 and spring 300 are positioned and dimensioned to locate guide element 294 in spaced relationship with the upper lap of conveyor 10 less than the diameter of a bowling ball.

In operation, a ball passing through pit cushion cutout 46 pivots guide element 294 upwardly as the ball moves into the bight formed by conveyor 52 and nose 295 of element 294 and is held therein by nose 295. Such ball is frictionally engaged therebetween and travelled by conveyor 52 from guide element 294 onto fixed rails 290 and thence to an elevated point of discharge at the upper extremity of rails 290. As a ball is travelled upwards by conveyor 52 towards fixed rails 290, guide element 294 is returned to operative ball engaging position by spring 300. At the point of discharge rails 290 are provided with a generally horizontal support 304 having a rounded nose 306 which is operative with conveyor 52 to release balls from between conveyor 52 and rails 290 and conduct them onto a suitable ball return track (not shown).

Occasionally, a ball travels or is thrown along the gutter of alley A adjacent kickback K. To prevent such ball from entering directly into the ball return mechanism 50 without first having its momentum retarded, there is provided a modified form of the present invention, illustrated in FIGURES 7 and 8 and in which like figures designate like parts. In this modification, ball channel 40 conducts balls obliquely across pit P into a recess 400 formed in kickback K. Pit cushion 402 has a cutout 404, a portion 403 of which adjacent kickback K is aligned with the gutter (not shown) of alley A. Platform 405 is provided, adjacent kickback K, with a ball

guide 406 having a curved, bevelled edge 408, generally aligned with arcuate recess 400 in kickback K.

A ball moving along the gutter (not shown) in alley A and into pit P contacts portion 403 and is deposited into channel 40 for movement into recess 400 of kickback K. Such ball then is conducted along curved channel 410 formed by edge 408 of guide 406 and recess 400 into the range of operation of ball return mechanism 50. Such arrangement ensures that all balls thrown or moved into the pit from alley A move safely towards the ball return mechanism. 10

What I claim is:

1. A bowling ball handling and return mechanism comprising a ball engaging and lifting conveyor, means mounting said lifting conveyor in the pit of a bowling alley, a substantially vertical ball track mounted in spaced ball-elevating relationship with said lifting conveyor, a ball return runway located adjacent the upper end of said track, a ball conveyor in said pit, a ball guide element at the lower end of said track, means mounting at least said element for vertical movement relative to said ball conveyor and yieldably biasing said element downwardly to a normal position at a distance above said ball conveyor which is less than the maximum diameter of a bowling ball, said element being displaceable upwardly from said normal position by a ball delivered thereto by said ball conveyor, thereby to permit the movement of the ball beneath said element and the engagement of said ball with said engaging and lifting conveyor, and means for driving the last-mentioned conveyor to elevate the engaged ball onto said ball track for movement therewith and to said return runway. 15

2. The invention as defined in claim 1 wherein said lifting conveyor and track are mounted at one side of said pit adjacent one of the kickbacks of said alley and wherein said ball conducting means includes a travelling pit-wide conveyor, means mounting said pitwide conveyor in said pit for conducting pins and balls rearwardly thereof, a pit cushion, means mounting said pit cushion transversely of said pit with the bottom of said cushion spaced from said pitwide conveyor less than the diameter of a bowling ball but greater than the maximum diameter of a bowling pin, said pin cushion being operative to separate pins and balls on said pitwide conveyor, guide elements, means mounting said guide elements beneath the upper lap of said pitwide conveyor in front of said pit cushion for forming a ball channel across and adjacent one side of said pit, an aperture in one side of said pit cushion aligned with said ball channel and the first mentioned conveyor for effecting movement of a ball in said channel past said cushion and into the range of operation of said lifting conveyor. 40

3. The invention as defined in claim 2 wherein said alley kickback adjacent said ball return mechanism is provided with a recess, and wherein said guide elements forming said ball channel have a portion thereof cooperating with said recess for forming a portion of said ball channel through said recess and including means mounting said pit cushion with a portion thereof aligned with the gutter of said alley adjacent said kickback provided with said recess whereby all balls deposited into said pit engage a portion of said pit cushion prior to entering into the range of operation of said lifting conveyor. 45

4. Bowling ball handling and return mechanism for use with a bowling alley having a pit at one end comprising a ball engaging and lifting conveyor having a travelling, substantially unbroken continuous ball engaging surface, means mounting said conveyor in said pit, a substantially vertical ball track, a ball return runway located adjacent the upper end of said track, a ball delivery device, a ball guide element mounted on the lower end of said track and above said device a distance less than the maximum diameter of a bowling ball, means mounting at least a portion of said track for upward vertical movement relative to said conveyor, means for operating 50

said device to deliver balls in said pit beneath said guide element, said movable portion of said track being constructed and arranged to be urged upwardly by a ball delivered beneath said guide element and then urged downwardly by gravity and rotation of ball to effect an engagement of said ball by said conveyor and prevent another ball from being moved by said device beneath said element, and means for driving said conveyor to elevate said engaged ball along said vertical ball track to said ball return runway. 5

5. Ball return mechanism for use with a bowling alley having a pit at one end comprising a ball engaging and lifting conveyor having a travelling substantially unbroken continuous ball engaging surface, means mounting said conveyor in said pit adjacent one of the kickbacks of said alley, a substantially vertical ball track, a ball return runway located adjacent the upper end of said track, a ball guide element mounted on the lower end of said track, a ball conducting device located beneath said element a distance less than the maximum diameter of a bowling ball, for conducting balls only delivered into said pit to said guide element, means mounting said track for upward vertical movement relative to said conveyor in response to its movement beneath said 20 guide element to effect engagement of said ball by said conveyor and for downward movement to prevent a second ball from moving beneath said element until said first ball is delivered onto said runway, and means for driving said conveyor to elevate said engaged ball along said vertical ball track to said return runway. 25

6. The invention as defined in claim 5 wherein said track mounting means, and said conveyor are constructed and arranged to maintain said track in depressed position by a ball moved therealong by said conveyor whereby 30 only one ball at a time may be delivered onto said return runway. 35

7. The invention as defined in claim 5 wherein said track mounting means includes a pair of spaced frames, means associated with each frame and freely supporting said frame for upward and downward movement, said frames and frame support means mounting said track for vertical movement relative to said conveyor. 40

8. The invention as defined in claim 5 wherein said track mounting means includes a pair of spaced links, means mounting said links on each side of said tracks, a second pair of spaced links, means mounting said second pairs of links in parallel spaced relationship with said first pair of links, said links supporting said track for substantially vertical movement relative to said conveyor. 45

9. The invention as defined in claim 5 wherein said conveyor and track are mounted at one side of said pit and wherein said ball conducting means includes a travelling pitwide conveyor in said pit for conducting pins and balls rearwardly thereof, a pit cushion, means mounting said pit cushion transversely of said pit with the bottom of said cushion spaced from said pitwide conveyor less than the diameter of a bowling ball but greater than the maximum diameter of a bowling pin, said pit cushion being operative to separate pins and balls, guide elements, means mounting said guide elements beneath the upper lap of said pit conveyor in front of said pit cushion for forming a ball channel across and adjacent one side of said pit, an aperture in one side of said pit cushion aligned with said ball channel and said lifting conveyor for effecting movement of a ball in said channel past said cushion and into the range of operation of said lifting conveyor. 50

10. Ball return mechanism for use with a bowling alley having a pit at one end thereof comprising a ball engaging and lifting conveyor having a travelling substantially unbroken continuous ball engagement surface, means mounting said conveyor in said pit adjacent one of the kickbacks of said alley, a substantially vertical ball track, means mounting said ball track in fixed spaced relationship with the ball engaging surface of said conveyor, a 70

ball return runway located adjacent the upper end of said track, a ball guide element adjacent the lower end of said track, means for conducting beneath said element a ball delivered into said pit, means normally supporting said element at a level where the same is engageable by said ball but also mounting said element for displacement upwardly by said ball conducted therebeneath, said element having a rounded lower nose section engageable with a ball delivered thereto by said conveyor to effect said displacement of the element, means yieldably biasing said element downwardly toward said level thereof, thereby to resist the movement of a ball beneath the ball guide element, and means for driving said conveyor to elevate an engaged ball along said vertical track to said runway.

11. The invention as defined in claim 10 wherein said lifting conveyor and track are mounted at one side of said pit and wherein said ball conducting means includes a travelling pit-wide conveyor in said pit for conducting pins and balls rearwardly thereof, a pit cushion, means mounting said pit cushion transversely of said pit with the bottom of said cushion spaced from said pitwide conveyor less than the diameter of a bowling ball but greater than the maximum diameter of a bowling pin, said pit cushion being operative to separate pins and balls, guide elements, means mounting said guide elements beneath the upper lap of said pitwide conveyor in front of said pit cushion for forming a ball channel across and adjacent one side of said pit, a recess in said one kickback aligned with said ball channel and said lifting conveyor for effecting movement of a ball in said channel around the end of said cushion and into the range of operation of said lifting conveyor.

12. A bowling ball handling and return mechanism comprising a ball engaging and lifting conveyor, means mounting said lifting conveyor in the pit of a bowling alley, a substantially vertical ball track mounted in spaced ball-elevating relationship with said lifting conveyor and having a ball guide element at its lower end, a ball return runway located adjacent the upper end of said track, a rearwardly travelling ball conveyor in said pit, means mounting said track for vertical movement relative to the first-mentioned conveyor and normally maintaining said track at a lower position in which said ball guide element is spaced a distance above said ball conveyor which is less than the maximum diameter of a bowling ball, said track being displaceable upwardly from said normal position by a ball delivered thereto by said ball conveyor to permit delivery of the ball to said first-mentioned conveyor, and means for driving said first-mentioned conveyor to elevate the engaged ball onto said ball track for movement therealong and to said return runway, said track being maintained by said ball in said lower position during elevation of the ball by said first-mentioned conveyor, thereby to obstruct momentarily the delivery of another ball thereto.

13. A bowling ball handling and return mechanism for use with a bowling alley having a pit at one end thereof comprising ball engaging and lifting conveyor means in said pit adjacent one of the kickbacks of the alley, a travelling pit-wide conveyor in said pit for conducting pins and balls rearwardly thereof, a pit cushion extending in front of said conveyor means across substantially the width of the last-mentioned conveyor with vertical spacing therefrom less than the diameter of a bowling ball

but greater than the maximum diameter of a bowling pin, said pit cushion being operative to separate pins and balls, and means for guiding a bowling ball toward the one end of said cushion adjacent said one kickback, said one kickback having a recess therein opposite said one cushion end and aligned with said conveyor means, said recess effecting the movement of a bowling ball around said one end of the cushion enroute to said conveyor means.

14. A bowling ball handling and return mechanism for use with a bowling alley having a pit at one end thereof comprising a ball engaging and lifting conveyor having a travelling substantially unbroken continuous ball engaging surface, means mounting said conveyor in said pit adjacent one of the kickbacks of said alley, a substantially vertical ball track, a ball return runway located adjacent the upper end of said track, a ball guide element mounted on the lower end of said track, a ball conducting device located beneath said element a distance less than the maximum diameter of a bowling ball for conducting balls only delivered into said pit to said guide element, means mounting said track for upward vertical movement relative to said conveyor in response to its movement beneath said guide element to effect engagement of said conveyor by said ball and for downward movement to prevent a second ball from moving beneath said element until said first ball is delivered onto said runway, and means for driving said conveyor to elevate said engaged ball along said vertical ball track to said return runway, said means for mounting the track comprising a pair of vertically spaced horizontal cross frames supporting said track and each being hollow to provide a vertical guide, and rods received within said cross frames and supported from the face of said one kickback, whereby said frames are vertically slidable on side rods.
15. A bowling ball handling and return mechanism comprising a ball engaging and lifting conveyor, means mounting said conveyor in the pit of a bowling alley, a substantially vertical ball track mounted in spaced ball-elevating relationship with said conveyor, a ball return runway located adjacent the upper end of said track, a ball conveyor in said pit, a ball guide element at the lower end of said track means mounting at least said element for vertical movement relative to said ball conveyor and yieldably biasing said element downwardly to a normal position at a distance above said ball conveyor which is less than the maximum diameter of a bowling ball, said element being displaceable upwardly from said normal position by a ball delivered thereto by said ball conveyor, thereby to permit the movement of the ball beneath said element and the engagement of said ball with said engaging and lifting conveyor, and said element thereafter being momentarily maintained in said normal position through the positive action of a ball being lifted by said ball engaging and lifting conveyor, thereby to prevent the movement of a second ball beneath said element during the lifting of the preceding ball.
